TONGS

John William Callahan, Wellsboro, Pa.

Application July 1, 1935, Serial No. 29,412

4 Claims. (Cl. 294—16)

The invention relates to tongs and more especially to lifting tongs for handling, turning and holding wood, stone, iron, piping or other materials.

The primary object of the invention is the provision of tongs of this character, wherein the jaws are of a kind to enable a firm grip to be had upon a load and the gripping action is assured through leverage transmitted thereto when the work is to be lifted or conveyed from one locality to another.

Another object of the invention is the provision of tongs of this character, wherein hand lifting of objects or material can be had without liability of the dropping of the load as a firm grip is assured when the material or load is raised from a resting position.

A further object of the invention is the provision of tongs of this character, which are simple in construction, thoroughly reliable and effective in operation, strong, durable, readily and easily handled and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a perspective view of tongs constructed in accordance with the invention showing the same gripping a load.

Figure 2 is an elevation with the tongs open and free of a load.

Figure 3 is a sectional view on the line 3—3 of Figure 1 looking in the direction of the arrows.

Figure 4 is a fragmentary sectional view on the line 4—4 of Figure 1 looking in the direction of the arrows.

Similar reference characters indicate corresponding parts throughout the several views in the drawing.

Referring to the drawing in detail, the tongs constituting the present invention comprise a pair of straight jaw members 5, these at the gripping sides thereof are provided with biting teeth 6 so that upon the closing in of the jaws 5 with respect to a piece of work the teeth 6 will firmly bite and grip such work so as to avoid the dropping thereof when held between the jaws. The jaws 5 having integrally formed therewith shanks 7 which are disposed at substantially right angles thereto, these being arranged side by side and reversed to each other. Embracing the

shanks 7 is a collar 8 through which said shanks slide in the opening and closing movements of the jaw members 5.

At the outer ends of the shanks 7 are upturned ears 9 having several spaced holes 10 therein for selectively accommodating pivot pins 11 which also are selectively engaged in spaced holes 12 provided in actuator levers 13, these being loosely connected by pivots 14 to the jaw members 5.

Integral with the levers 13 are angularly disposed handles 15 arranged in crossed relation to each other and terminate in loop-like hand grips or hand holds 16. The grips or holds 16 are slightly downwardly bent with relation to the handles 15 so that when the jaw members 5 are in gripping relation to a piece of work 17 the grips or holds 16 will be in substantially a horizontal plane.

In the use of the tongs the work to be lifted 20 thereby is placed between the jaw members 5 and by leverage on the handles 15 when hand grip is had at the grips or holds 16 the jaws will be moved toward each other and in gripping engagement with the work 17 so as to firmly grasp the 25 same whereby on the raising of the tongs the work will be elevated or lifted. In actuating the handles 15 the shanks 7 of the jaw members 5 slide through the collar 8, the latter being held fixed by a fastener 18 with respect to one of the 30 shanks 7. Maximum leverage is had on the jaw members 5 by the arrangement of the handles 15 and the connection of the levers 13 with the shanks 7 and the jaw members. It will be noted that each lever 13 is connected with one jaw 35 member 5 and also connected with the shank 7 of the other jaw member, there being a toggle action on the jaw members.

Associated with one of the handles is a guide 40 rod 19, the same being engaged at one end with the pivot 11 connecting this handle with the shank 7 and the other end attached at 20 to the said handle, the rod 19 being in bridging relation to the other handle so that these handles 45 will be guided with relation to each other and tensioned in their crossed disposition one with the other.

What is claimed is:

1. In tongs of the character described, a pair 50 of opposed jaw members having shanks at substantially right angles thereto slidably connected with each other and reversely disposed with respect to one another, and handle operated levers each pivoted to the shank of one jaw member and 55

to the other jaw member for the movement toward and away from each other.

2. In tongs of the character described, a pair of opposed jaw members having shanks at substantially right angles thereto slidably connected with each other and reversely disposed with respect to one another, handle operated levers each pivoted to the shank of one jaw member and to the other jaw member for the movement toward and away from each other, and hand grips having handle connection with said levers.
3. In tongs of the character described, a pair of opposed jaw members having shanks at substantially right angles thereto slidably connected with each other and reversely disposed with respect to one another, handle operated levers each pivoted to the shank of one jaw member and to the other jaw member for the movement to-

ward and away from each other, hand grips having handle connection with said levers, and a collar embracing the shanks and fixed with relation to one of the same.

4. In tongs of the character described, a pair of opposed jaw members having shanks at substantially right angles thereto slidably connected with each other and reversely disposed with respect to one another, handle operated levers each pivoted to the shank of one jaw member and to the other jaw member for the movement toward and away from each other, hand grips having handle connection with said levers, a collar embracing the shanks and fixed with relation to one of the same, and roughened work engaging faces on said jaw members.

JOHN WILLIAM CALLAHAN.
